DESIGN FOR A SAMPLE DISPLAY STAND FOR FLOOR COVERINGS

James H. Millholland, Philadelphia, Pa., assignor to Sandura Company, Inc., a corporation of Delaware

Application May 27, 1936, Serial No. 62,872

Term of patent 7 years

To all whom it may concern:

Be it known that I, James H. Millholland, a citizen of the United States, residing at Philadelphia, in the county of Philadelphia and State of Pennsylvania, have invented a new, original, and ornamental Design for a Sample Display Stand for Floor Coverings, of which the following is a specification, reference being had to the accompanying drawing, forming part thereof.

Fig. 1 is a front elevation of a sample display stand for floor coverings showing my new design; Fig. 2 is a side elevation; and

Fig. 3 is a top plan view thereof.

What I claim is:

The ornamental design for a sample display stand for floor coverings, as shown.

In testimony whereof, I affix my signature.

JAMES H. MILLHOLLAND.
